Charles T. Libby.

UNITED STATES PATENT OFFICE.

CHARLES T. LIBBY, OF PORTLAND, MAINE.

LINOTYPE-MACHINE.

No. 846,584.

Specification of Letters Patent.

Patented March 12, 1907.

Application filed July 20, 1903. Serial No. 166,275.

To all whom it may concern:

Be it known that I, CHARLES T. LIBBY, a citizen of the United States, residing at Portland, in the county of Cumberland and State of Maine, have invented certain new and useful Improvements in Linotype-Machines; and I do hereby declare the following to be a full, clear, and exact description of the invention, such as will enable others skilled in 10 the art to which it appertains to make and use the same.

This invention relates to improvements in machines of the general character of the so-called "Mergenthaler" linotype-machine 15 shown and described in Letters Patent of the United States No. 436,532, dated September 16, 1890.

It relates to means for reciprocating the assembling-elevator by automatic actuating 20 mechanism set in motion by the operator each time it acts.

It also relates to means for reciprocating the assembling-elevator by automatic actuating mechanism that runs continuously and 25 independently of the operator.

It also relates to means for changing the machine from the former class to the latter and back again.

It also relates to means for controlling the 30 automatic-actuated mechanism and for bringing it into action at the will of the operator.

It also relates to certain details of construction hereinafter described and specifically explained.

The existing machine is started by the line-delivery carriage being released by the putting up of the assembling-elevator, which the operator does by a hand-lever each time he 40 has assembled a matrix-line, and the machine automatically stops after casting the line thus sent up, unless the next line has already been sent up, in which case the start-and-stop mechanism of the machine is thrown 45 out and its main driving-shaft instead of stopping runs continuously. By my improved mechanism the assembling-elevator is put up automatically and is either set in operation by the operator each time he has assembled 50 a matrix-line or at his option the line-delivery-carriage shaft on its return through intermediate mechanism starts the assembling-elevator, thus making the machine constant-running irrespective of the operator.

55 In the drawings herewith accompanying and making a part of this application, Figure

1 is a perspective view of a portion of the Mergenthaler machine, showing my improvements applied thereto. Fig. 2 is a sectional detail view of the latches, their operating-levers and springs, the position of the several parts in both views being that which they occupy at the instant the assembling-elevator releases the line-delivery carriage; and Fig. 3 is a detail view of the latches and 65 their springs.

Same reference characters refer to like parts.

In said drawings, A represents the base; B, the front of the frame; C, the line-delivery carriage; D, the line-delivery-carriage lever; E, the line-delivery-carriage shaft; F, the assembling-elevator; G, the keyboard; H, a pivoted latch for retaining the line-delivery carriage; I, the line-delivery-carriage-releasing pin; J, the needle on the assembling-elevator for operating said releasing-pin; K, the hook for supporting the assembling-elevator; L, the assembling-elevator-releasing bar; M, the assembling-elevator lever, and N the assembling-elevator-lever link. These parts 75 may be substantially the same and operate in substantially the same manner as in the aforesaid Mergenthaler machine.

In carrying out my invention I mount inside the column of the machine a cross-shaft 1 of the same diameter as the line-delivery shaft, at right angles with it, extending to the right, and connect the two by bevel-gear 2 in such manner that the rocking motion of 90 the line-delivery shaft leftward and rightward, as in the existing machine, imparts to my cross-shaft a rocking motion at right angles thereto—viz., frontward and rearward. Only segments are necessary, because the 95 line-delivery shaft only moves about forty-five degrees and back again. On this cross-shaft I place adjustably a lever 3, extending downward. I face the bevel-gear so that when the line-delivery-carriage shaft makes 100 its first or leftward movement the bottom end of the lever, which is forked, comes forward, returning rearward when the line-delivery shaft returns to the right. The fork of the forked lever reaches down on both 105 sides of a threaded hook 4, adapted to have a rearward and frontward movement through a hole in bracket 5, which is fastened to the back side of the column, rearward impelled by said forked lever, frontward drawn by 110 spring 7 below mentioned. This threaded hook carries two nuts 6 and 8 and check-nuts

to each. Nut 6 is behind bracket 5 and adjustably limits the forward movement of the threaded hook. Nut 8, placed in the path of the forked lever, adjustably determines the rearward position of the threaded hook. The hook end of the threaded hook hooks into the rearward end of a close spiral spring 7, similar to the balancing-spring on the existing machine, but more efficient. 5 The rear end of the spring is elongated so as to pass through to the inside of the frame of the machine, where it hooks into the threaded hook. The front end of spring 7 attaches to the downward arm of bell-crank 26 on the 10 assembling-elevator-lever shaft, the other arm thereof reaching under the lever for the purpose of raising the elevator when the spring contracts.

On the bottom of the assembling-elevator 20 I screw a shoulder or ledge 9, extending front and back and curved slightly on top to fit the holding-face of the latch below mentioned.

Under the assembling-elevator I place a bracket 10, which fastens to the frame of the 25 machine, preferably having an arm at the bottom end reaching to the right, so as to fasten by the same screws that hold the key-board in place. On the bracket I place a latch 11, adapted to engage the ledge, 30 screwed to the bottom of the assembling-elevator. This latch I arrange to be doubly controlled, as specified below.

On the end of the line-delivery shaft or the hub of the line-delivery lever, on its left 35 edge, I place a stud 12. On the stud I mount loosely a lever 13, adapted to move in a vertical path and of the right length and so offset as to lay across the tail of the latch. On the top edge of said loose lever 13 I fasten 40 one end of a flat spring 15, so positioned that the free end of said spring is in the path of eccentric screw 14, mounted on the right-hand edge of the end of the line-delivery-carriage shaft or hub. The strength of this 45 flat spring when impinged by said eccentric screw upon the return movement of the line-delivery-carriage shaft is sufficient to unlatch latch 11 under some circumstances and under other circumstances not strong 50 enough, as hereinafter described. Under the latter circumstances when the eccentric screw engages the flat spring the latter yields and closes down toward the loose lever. The latter position of the parts is shown in Fig. 2.

55 Upon the withdrawal of 17 by the operator spring 15 thereupon actuates loose lever 13 to unlatch latch 11. The screw is made eccentric in order to adjust the time of its unlatching the latch to the moment when the 60 line-delivery carriage has returned.

Under the tail of the latch I place one end of an intermediate lever 17, its other end engaging one end of the key-lever 18. In front of the other end of the intermediate 65 lever I place a flat spring 19, strong enough to

raise the key-lever and at the same time to overcome the loose-lever spring. By this mechanism the loose lever can throw out the latch when the intermediate lever is away; otherwise not.

70 On the bracket below the latch I place another latch 20, arranged when not thrown out to engage the intermediate lever, and I extend the tail of the main latch to engage the tail of the intermediate lever-latch. I 75 adapt the intermediate lever to go lower when put down by the key-lever or when locked down by the clasp hereinafter mentioned than when put down by the fall of the assembling-elevator or by the return of the 80 eccentric screw. I cut the holding-face of the intermediate lever-latch so low as to latch in only when the intermediate lever is in its lowest position, and I so cut the length of its holding-face with relation to the 85 length of the tail of the main latch that the intermediate lever is let up by its latch at the same instant or a little later than the assembling-elevator. Under the intermediate lever-latch I place a flat spring 21, tending to 90 hold it latched. By this arrangement the intermediate lever is latched down if put down by the key-lever when the main latch is latched, otherwise not, and if thus latched it is unlatched when the loose lever or the 95 elevator throws out the main latch.

The two latch-springs 16 and 21 combined I make weaker than the loose-lever spring 15; but the main-latch spring 16 and the intermediate lever-spring 19 combined I make 100 stronger than the loose-lever spring combined with the weight of the key-lever.

At right angles to the key-lever I place a clasp 22, adapted by means of its shoulder, which when swung to the left overreaches 105 the top edge of the key-lever, to lock it down. The clasp, key-lever, intermediate lever, and two latches are all pivotally mounted on the bracket, the main latch in a slot in the bracket, and the intermediate lever-latch in a slot in a spur 28 on the bracket. On the top of the bracket I make a shoulder to prevent the latch going too far over when the elevator is up.

By adjusting the forked lever on the cross-shaft and the nut engaging the fork the elevating-spring—namely, 7—when the forked lever is in its extreme rearward position is adjusted to have sufficient tension to carry up the elevator. By adjusting the nut near 115 the end of the threaded hook the elevating-spring is adjusted in its second position, so that its tension when the forked lever is away from nut 8 is adapted to letting the elevator fall down without jar. The elevating-spring is adapted to have the required 120 difference in strength from the change in its anchorage between nuts 8 and 6, due to the movement of the forked lever over about one-third of its course or less, keeping with- 125 130

in the movement of the line-delivery carriage in clearing the matrix-line from the assembling-elevator and letting the spring down to its second position before hook K is disengaged. These adjustments are aided by an auxiliary balancing and adjusting spring 23, not, however, essential, anchored at one end to a threaded hook 24, set in a pin 25, set in the frame of the machine and at the other end attached to bell-crank 26.

The elevating-spring I prefer to attach nearer the shaft than the assembling-elevator-balancing spring in the existing machine, the other spring farther.

15 The machine thus constructed may be operated in three ways:

First, when the operator touches the key every time a line is ready. In this case the machine is in ready position when the forked lever is in its extreme rearward position, holding the elevating-spring at its greater tension, the elevator latched down, the eccentric screw pressing on the loose lever and that on the tail of the main latch, but not hard enough to throw it out so long as the intermediate lever is pressing up on the tail of it. The operator touching the key when his line is ready lowers the end of the intermediate lever. The latch follows it, actuated by the loose-lever spring, and is thus thrown out. The elevating-spring contracts, a direct pull between nut 8 and the downward arm of bell-crank 26 raising the elevator. The elevator arrives up and releases the line-delivery carriage, which starts over to the left. At this moment the forked lever, which is actuated by the line-delivery-carriage shaft, starts frontward, and thus begins to release the tension of the elevating-spring, and the eccentric screw begins to withdraw from the loose lever. The line-delivery carriage has traveled about one-third of its course over before the matrix-line has cleared the assembling-elevator. After the line has cleared, the releasing-bar then knocks off the assembling-elevator hook and lets the assembling-elevator drop. Before this happens the forked lever has let the elevating-spring down to its second position, held by the nut 6 engaging the back of the bracket 5, and has cleared its nut. The eccentric screw is passing an idle course, with the loose lever left behind. The latch is in. The elevator falls, its fall broken by the elevating-spring in its second position. It arrives down, throwing out the main latch, pushing down the intermediate lever, but not far enough to latch, and also throwing out the intermediate latch and letting up the intermediate lever if latched down. Nothing happens while the line-delivery carriage completes its course over and about two-thirds of its way back. The forked lever then reengages its nut and gradually returns the elevating-spring to its greater tension. The eccentric screw en-

gages the loose-lever spring and presses on it; but the latch is held in by the intermediate lever. All parts are now in the same position as when the operator touched the key.

The second method of operation is when the operator hits the key before the line-delivery carriage gets back. At such time the main latch is in, as the eccentric screw is away from the loose lever, and the intermediate latch is only held out by its nose pressing against the side of the intermediate lever. The operator touches the key, lowering the intermediate lever from under the main latch, which, however, remains in; being affected only by its own spring. The intermediate lever-latch latches the intermediate lever down, leaving the key down. This situation continues until the line-delivery shaft returns. The eccentric screw then engages the loose lever, throwing out both latches. The elevator starts up. The intermediate lever and key come up. The situation now is the same as if the elevator had been released by touching the key with the line-delivery carriage back.

90 The third method of operation is when the key-lever is locked down, thereby locking the intermediate lever out of action. This leaves the latch controlled only by the loose lever. The operation under this condition resembles the second method, as each return of the line-delivery shaft throws out the latch, leaving the burden on the operator to have his line ready to go up in readiness for that. If bad copy or other interruption prevents such 100 readiness, the operator releases the key-lever, thereby bringing the intermediate lever again into action, by which step an instant change to the first method of operating the machine is effected.

105 The advantages of my improved machine are as follows: It is optional with the operator to have it either a constant-running or a start-and-stop machine. The former method is valuable to the large number of operators 110 who are able to set news measure to the full speed of the machine, and who are thus saved the labor and nervous strain of putting up the assembling-elevator and watching the movement of the machine for the proper time of doing so—in fact, have nothing left to do but to be sure their line is set before the elevator goes up and then enjoying an instant's relaxation and an opportunity to glance at copy while the assembling-elevator 115 automatically goes up and returns. Furthermore, operators who are otherwise unable to set lines to the full speed of the machine will have their speed increased, because my improved machine will save all interruption of their attention to copy caused by using the hand-lever to put up the assembling-elevator and the time while the elevator is passing up and back will enable them to be all ready to set the next line immediately the 120 125 130

elevator is returned. Upon any interruption in completing a line of mats the operator may instantly change the machine to the start-and-stop form by throwing off the clasp.

5 Having thus described my invention and its use, I claim—

1. In a linotype-machine, in combination with the vertically-movable assembling-elevator, mechanism of varying force efficient alternately to raise the elevator and counter-balance its fall by gravity, means to periodically hold down and release said elevator.

2. In a linotype-machine, in combination, 15 an assembling-elevator, elevator-reciprocating mechanism, means for alternately taking away from and restoring to said reciprocating mechanism the force to raise said elevator and means for periodically detaining the 20 elevator at either end of its movement.

3. In a linotype-machine, in combination, 25 an assembling-elevator, mechanism adapted in one position to raise said elevator and in another position to let it fall without jar, means actuated by a moving part of the machine to shift said mechanism alternately between the two positions.

4. In a linotype-machine, in combination, 30 an assembling-elevator, a spring provided with one anchorage from which it is adapted to raise said elevator, and with another anchorage from which it is adapted to let the elevator fall without jar, means to alternately shift said spring from one anchorage 35 to the other.

5. In a linotype-machine, in combination, 40 a vertically-movable assembling-elevator, a spring for raising said elevator, means for taking away the strength of said spring enough and quick enough to let said elevator return, means for temporarily holding the elevator 45 down and controlling means.

6. In a linotype-machine, in combination, 45 the assembling-elevator, a spring tending to raise said elevator, means for periodically taking away the force of said spring enough merely to break the fall of said elevator, a latch for holding up said elevator temporarily, means for automatically throwing out 50 said latch and means for regulating said spring.

7. In a linotype-machine, in combination, 55 the line-delivery shaft, a latch, three springs, the first spring tending to hold said latch in, a lever also adapted to yieldingly hold said latch in actuated by the second spring, a lever on the line-delivery shaft yieldingly actuated by said shaft and tending to throw said latch out through the medium of the third spring, 60 said third spring being strong enough to overpower the first spring above mentioned but not the first and second combined, a key-lever adapted to be operated manually to withdraw the first-mentioned lever, whereby said 65 latch is unlatched when both the line-deliv-

ery shaft is acting and the first-mentioned lever withdrawn.

8. In a linotype-machine, an assembling-elevator, elevator-reciprocating mechanism, a latch adapted to temporarily hold down 70 said elevator, two means for holding said latch in engagement and means for overpowering said two means successively.

9. In a linotype-machine, in combination, 75 an assembling-elevator, means for raising said elevator, a latch under double control for holding said elevator down, one adapted to act arbitrarily, the other automatically, and means by which the assembling-elevator, when the arbitrary releasing mechanism has 80 been brought into operation before the automatic releasing mechanism has acted, remains waiting until the latter acts.

10. In a linotype-machine, in combination, 85 an assembling-elevator, means to raise said elevator, a latch to hold said assembling-elevator down, two levers to operate said latch adversely, one actuated automatically by some moving part of the machine to throw it out, the other actuated by a spring to hold it 90 in, means to withdraw the latter operated manually.

11. In a linotype-machine, in combination, 95 the assembling-elevator, means for raising and letting it down, a latch to hold it down two levers acting adversely adapted to operate said latch, two springs tending to hold said levers in engagement with the latch, one lever tending to hold the latch in, a spring engaging the latch with strength enough only 100 to hold the latch in when both levers are away, the other lever operated automatically, to throw it out and actuated by the line-delivery shaft, the latter when both are in operation being the weaker, and the former 105 being adapted to be operated manually and fitted with a latch adapted to prevent its re-engaging before the assembling-elevator has gone up.

12. In a linotype-machine, in combination, 110 the line-delivery shaft, a latch, a spring tending to hold said latch in, a lever also adapted to yieldingly hold said latch in actuated by another spring, a lever on the line-delivery shaft yieldingly actuated by said 115 shaft and tending to throw said latch out, strong enough to overpower the first spring above mentioned but not the two combined, a key-lever adapted to be operated manually to withdraw the first-mentioned lever, another latch adapted to latch the first-mentioned lever down operated adversely by a spring under it to hold it in, and the tail of the first-mentioned latch over it to throw it out, whereby the latch when the first-mentioned lever is manually withdrawn while the lever actuated by the line-delivery shaft is not acting remains latched until the lever on the line-delivery shaft acts and then is unlatched.

13. In a linotype-machine, in combination, the assembling-elevator, mechanism adapted to raise the elevator and let it down, mechanism doubly controlled for latching the elevator down, mechanism for arbitrarily releasing the elevator, a hand-operated clasp adapted to lock the last-mentioned mechanism out of action, the line-delivery carriage and its shaft, mechanism actuated by the latter to release the elevator.
14. In a linotype-machine, in combination, an assembling-elevator, mechanism for reciprocating the same, a latch adapted to hold the elevator down, a spring tending to hold said latch in, a lever also adapted to yieldingly hold said latch in a spring to actuate said lever, the line-delivery carriage and its shaft, a lever on the line-delivery shaft yieldingly actuated by said shaft and tending to throw said latch out, strong enough to overpower the first spring above mentioned but not the two combined, a key-lever adapted to be operated manually to withdraw the first-mentioned lever, another latch adapted to latch the first-mentioned lever down and to be thrown out by the tail thereof, a spring adapted to hold said latch in, a clasp manually operated to lock the key-lever down.
15. In a linotype-machine, in combination, the assembling-elevator, a spring tending to raise said elevator, a latch for holding said elevator up, means for automatically throwing out said latch, allowing the elevator to fall, and means for controlling the action of said elevator-spring, whereby the same may act to break the fall of the elevator.
16. In a linotype-machine, the vertically-movable assembling-elevator, a spring with both ends thereof subject to change position, the attaching end changing with the movements of the elevator and the anchorage end shifting from one hold to another hold adjustable to give said spring in the one position the necessary tension to raise the elevator and in the other position tension enough merely to let it fall without jar, in combination with devices for operating said spring and controlling said elevator.
17. In a linotype-machine, an attachment for operating the assembling-elevator comprising a spring and means for tensioning same enough to raise the elevator, for holding said spring at said tension while the elevator rises and for letting the spring down to a tension sufficient merely to let it fall without jar, operating substantially as described.
18. In a linotype-machine, the vertically-movable assembling-elevator and automatic actuating mechanism therefor, in combination with a spring-pressed latch to periodically hold said elevator down, a lever operated by a moving part of the machine to throw out said latch, key mechanism adapted to block the releasing motion of said lever automatically and to be thrown out manually.
19. In a linotype-machine, an assembling-elevator, elevator-actuating mechanism, a spring-pressed latch for periodically holding down said elevator, automatically-actuated mechanism for operating said latch, a device for automatically blocking the last-named mechanism adapted to be manually withdrawn.
20. In a linotype-machine, in combination, the assembling-elevator, elevator-actuated mechanism, a spring-pressed latch for periodically holding down said elevator, automatically-actuated mechanism for operating said latch, a device for automatically blocking the last-named mechanism adapted to be manually withdrawn, a device for locking the last-named device out of action.
21. In a linotype-machine, the assembling-elevator and automatic actuating mechanism therefor, in combination with a latch adapted to hold the elevator down, mechanism for automatically unlatching said latch and devices for automatically blocking and manually releasing the last-mentioned mechanism.
22. In a linotype-machine, the assembling-elevator and automatic actuating mechanism therefor, in combination with a latch adapted to hold the elevator down, mechanism for automatically unlatching said latch, devices for automatically blocking and manually releasing the unlatching mechanism, and devices connected with the blocking device for manually locking it out of and letting it into action.
- In testimony whereof I hereto affix my signature, in presence of two witnesses, this 18th day of July, 1903.
